(57) **CLAIM**

The ornamental design for an integrated eye wash and sink faucet, as shown and described.

DESCRIPTION

FIG. 1 is a left side elevational view of an integrated eye wash and sink faucet, showing our new design;

FIG. 2 is a front elevational view thereof;

FIG. 3 is a rear elevational view thereof;

FIG. 4 is a top plan view thereof; and,

FIG. 5 is a bottom plan view thereof.

The broken line showing of the handle in the Figures is for illustrative purposes only and forms no part of the claimed design.
